UNITED STATES PATENT OFFICE.

DUGALD J. KELLY, OF JOHNSTON CITY, ILLINOIS.

RAILWAY SWITCH-THROW AND MINE SWITCH-THROW.

1,391,547.

Specification of Letters Patent. Patented Sept. 20, 1921.

Application filed March 8, 1921. Serial No. 450,653.

To all whom it may concern:

Be it known that I, DUGALD J. KELLY, a citizen of the United States, residing at Johnston City, in the county of Williamson and State of Illinois, have invented certain new and useful Improvements in a Railway Switch-Throw and Mine Switch-Throw, of which the following is a specification.

10 This invention relates to railway switch operating apparatus, more particularly to the devices of this character employed in mine operations, and has for one of its objects to simplify and improve the construction and increase the efficiency and utility of devices of this character.

Another object of the invention is to provide a device of this character which may be manually operated by a brakeman or 20 other operator from a moving car without stopping the car.

With these and other objects in view the invention consists of such novel features of construction as hereinafter shown and described and then specifically pointed out in the claims, and in the drawings illustrative of the preferred embodiment of the invention.

Figure 1 is a plan view of a portion of a 30 railway track including the ties, a conventional switch, including the bridle bar and a part of the switch track, with the improved operating apparatus applied.

Fig. 2 is an enlarged sectional elevation 35 on the line 2—2 of Fig. 1.

Fig. 3 is a detail in section on the line 3—3 of Fig. 2.

Fig. 4 is a detail in section on the line 4—4 of Fig. 2.

40 Fig. 5 is a view similar to Fig. 2, illustrating a modification in the construction.

Fig. 6 is a plan view of the parts shown in Fig. 5.

The improved operative mechanism may 45 be adapted without material structural change to various forms of switches, but for the purpose of illustration is shown applied to a conventional split switch.

The ties are represented at 10, the continuous main line rail at 11, the combined main line and the side track rail at 12 and 13, the switch rails or "points" at 14 and 15, and the bridle or switch bar at 16, the latter coupled to the switch rails 14 and 15, these 55 parts being of the usual construction.

Pivoted at one end at 17, to one of the ties

10 is a relatively heavy lever member 18, extending over a plurality of the ties 10 and pivoted at the other end at 19 to the bridle or switch bar 16.

By this arrangement when the lever member 18 is moved laterally upon its pivot 17 the switch points 14 and 15 will be actuated.

Supported adjacent the rails 11 and 12 and bridging the same, is an oblong frame, 65 comprising vertical side members 20 and transverse head members 21, the latter being at a sufficient distance above the track to enable the cars with a man standing thereon to pass beneath without danger to the brake- 70 man on the car.

Mounted for rotation in bearing members 22 on the uprights 20 at one side of the track is a vertical rod 23 having a crank 24 at the lower end, and a ratchet member 25 at the 75 upper end.

The crank is coupled by a link 26 to the lever member 18 intermediate its end. Attached to one of the members 20 is a pawl device 27 which engages the teeth of the 80 ratchet member 25 to hold the rod 22 fixed for movement in one direction only.

Rising from the ratchet member 25 is a one way clutch element 28. Mounted for 85 rotation in bearings 29 on the vertical members 20 of the frame is an operating rod 30 having opposing one way clutch element 31 at the lower end co-operating with the one way clutch element 29, and semi crank element 32 at the upper end. A spring 33 is 90 arranged to hold the rod 30 yieldably for rotation in one direction only, and thus hold the clutch element 28 and 31 yieldably locked against the pawl 27. A tubular guide member 34 is suspended from the frame member 95 21 by hangers 35 to carry a pull cable 36, and connected to the crank element 32 and the other end projecting within reach of the brakeman on the car moving on the track.

As the car approaches the switch if it is to 100 be shunted or moved on the side track, the brakeman pulls downwardly on the cable 36 and rotates the rod 30, and throws the switch into open position or in position to move the car onto the side track. If the car is to 105 travel along the main line, then of course the brakeman pays no attention to the cable 36 but passes beneath it.

If a second car approaches and is also to 110 go on the switch track, the apparatus needs no attention, but if the next car is to run on the main line, another pull on the cable 36

will again actuate the rod against the spring 33 and reverse the movement of the lever member 18 and close the switch to the main line, as will be obvious.

If a train approaches on the main line from the opposite direction and the switch members 14 and 15 are closed to the switch track, then the clutch device opens the switch and the train proceeds on the main line, in 10 the usual manner.

The terminals of the tubular member 34 are preferably flared as shown so that the cable will run freely therein without binding or cutting.

15 In Figs. 5 and 6 a modification in the device is shown, the clutch element 28 being displayed by an operating crank rod 37 extending within reach of the brakeman on the car.

20 This modification can be used under certain circumstances if preferred, for instance in case the track is run into a contracted space so that there is not room for the overhead operative member 34.

25 The improved device is simple in construction, can be inexpensively manufactured and applied and adapted without material structural change to various forms of switches and the value of the track.

30 The preferred embodiment of the invention is disclosed in the drawings and set forth in the specification, but it will be understood that any modifications within the scope of the claims may be made in the con-

struction without departing from the principle of the invention or sacrificing any of its advantages.

Having thus described the invention what is claimed as new is:—

1. A switch operating mechanism comprising a lever member adapted to be coupled at one end to a switch bar and pivoted at the other end adjacent to one of the rails of a railway track, a crank rod mounted for rotation and coupled to the lever member intermediate its ends, a ratchet member connected to said crank rod, a stop pawl associated with said ratchet member, and means operative from a car for rotating the crank rod. 50

2. A switch operating mechanism comprising a lever member adapted to be coupled at one end to a switch bar and pivoted at the other end adjacent to one of the rails of a railway track, a crank rod mounted for rotation and coupled to the lever member intermediate its ends, a ratchet member connected to said crank rod, a stop pawl associated with said ratchet member, a clutch element carried by said crank rod, a spring controlled operating rod, an opposing clutch element carried by said operating rod, and means operative from a car for actuating said operating rod against the resistance of its spring. 65

In testimony whereof, I affix my signature hereto.

DUGALD J. KELLY.
